(57) **CLAIM**

The ornamental design for a display screen with lost wallet graphical user interface, as shown and described.

DESCRIPTION

The FIGURE is a front view of a display screen with lost wallet graphical user interface showing the new design.

The broken lines outside the dot-dash broken line showing an electronic device illustrate environment. The dot-dash broken line showing a display screen and the regular broken lines within showing elements of a graphical user interface illustrate portions of the article. None of the broken lines form part of the claimed design.
